DESIGN FOR A BASE FOR A DESK STAND

Benjamin W. Hanle, Elizabeth, N. J., assignor to Eagle Pencil Company, New York, N. Y., a corporation of Delaware

Application March 17, 1937, Serial No. 68,224

Term of patent 7 years

To all whom it may concern:

Be it known that I, Benjamin W. Hanle, a citizen of the United States and residing at Elizabeth, New Jersey, have invented a new, original, and ornamental Design for a Base for a Desk Stand, of which the following is a specification, reference being had to the accompanying drawing, forming part thereof, and in which

Fig. 1 is a top plan view of the base of the desk stand,

Fig. 2 is a side elevation of the base of the desk stand, and

Fig. 3 is a front view of the base of the desk stand.

I claim:

The ornamental design for a base for a desk stand substantially as shown.

BENJAMIN W. HANLE.
